CLAIM

The ornamental design for a floral display stand, as shown and described.

DESCRIPTION

FIG. 1 is a perspective view of a floral display stand, showing my new design;

FIG. 2 is a side elevational view thereof, the opposite side elevational view being a mirror image of that shown;

FIG. 3 is a top plan view thereof;

FIG. 4 is a bottom plan view thereof;

FIG. 5 is a perspective view of a floral display stand showing a second embodiment;

FIG. 6 is a side elevational view of FIG. 5, the opposite side elevational view being a mirror image of that shown;

FIG. 7 is a top plan view of FIG. 5;

FIG. 8 is a bottom plan view of FIG. 5;

FIG. 9 is a perspective view of a floral display stand showing a third embodiment;

FIG. 10 is a side elevational view of FIG. 5, the opposite side elevational view being a mirror image of that shown;

FIG. 11 is a top plan view of FIG. 9;

FIG. 12 is a bottom plan view of FIG. 9;

FIG. 13 is a perspective view of a floral display stand showing a fourth embodiment;

FIG. 14 is a side elevational view of FIG. 13, the opposite side elevational view being a mirror image of that shown;

FIG. 15 is a top plan view of FIG. 13;

FIG. 16 is a bottom plan view of FIG. 13.

FIG. 1FIG. 2FIG. 3FIG. 4

FIG. 5FIG. 6FIG. 7FIG. 8

FIG. 10
